UNITED STATES PATENT OFFICE.

CHARLES A. STURTEVANT, OF PLAINFIELD, NEW JERSEY, ASSIGNOR TO AMERICAN BANK NOTE COMPANY, A CORPORATION OF NEW YORK.

PRINTING-MACHINE.

1,026,936.

Specification of Letters Patent. Patented May 21, 1912.

Application filed November 11, 1911. Serial No. 659,794.

To all whom it may concern:

Be it known that I, CHARLES A. STURTEVANT, a citizen of the United States, residing at Plainfield, in the county of Union 5 and State of New Jersey, have invented certain new and useful Improvements in Printing-Machines, of which the following is a specification, reference being had therein to the accompanying drawings, which form a 10 part thereof.

My invention relates to printing machines, and more particularly to a class of multi-color rotary perfecting offset presses.

The main object of the invention is to 15 provide a press of this character wherein an impression may be simultaneously made upon both sides of the paper by the planographic off-set method, and such impressions may be taken without likelihood of the 20 smutting or spreading of the ink.

A further object is to provide such a press which may be used either as a perfecting 25 press or to make an impression upon one side of the sheet only, means being provided for rendering one planographic surface, or 30 set of planographic surfaces, inoperative while leaving the other fully operative.

A still further object is to provide a press 35 wherein the various mechanisms will be so constructed and associated as to permit the making of an impression upon one side of the sheet in a plurality of colors simultaneously, or in one color, as desired.

A still further object is to provide in a 40 machine of this character a main impression cylinder and an oppositely disposed impression cylinder, each of said cylinders acting as an impression cylinder, and, in relation to the other, as a platen cylinder, the impression surfaces of both cylinders consisting 45 of a resilient non-absorbent facing such as rubber; said main cylinder also carrying means whereby a planographic plate or plates may be secured thereto in a manner 50 to transfer to said other impression cylinder or the facing thereon, an impression in color, and having associated therewith one or more planographic cylinders adapted to be automatically shifted so as to be held out of engagement with the planographic plates upon 55 said cylinder while being caused to engage or bear upon the printing surface or rubber facing upon said main cylinder; and means

being provided whereby the damping and inking mechanism for the planographic 55 plates upon said main impression cylinder will be so shifted automatically as to be inoperative as to the printing surface or rubber facing carried by said main cylinder.

A still further object is to provide a machine of this character wherein the degree of pressure of the planographic plates upon the resilient printing surface, may be regulated to a nicety to compensate for wear upon, or the expansion or contraction of, 65 said printing surface.

A still further object is to provide simple and conveniently accessible means whereby the planographic plates upon the planographic or transfer cylinders, adapted to 70 normally bear upon the printing surface of the main cylinder, may be independently thrown, and held, out of the impression relation with said main cylinder.

A still further object is to provide means 75 whereby the main and the supplemental impression cylinders may be thrown out of or into the impression relation to control the operation of the machine independently of the main power.

A still further object is to provide means in conjunction with the impression cylinders or rollers, whereby a sheet of paper will be accurately positioned and fed between the two impression rollers and 85 delivered thereby to the sheet delivery mechanism.

A still further object is to so construct and associate the various mechanisms as to cause the damping and inking mechanisms 90 acting in relation to each planographic cylinder to be moved toward and from the main impression cylinders together with said planographic or transfer cylinders, while being capable of movement independently 95 thereof to facilitate the adjustment of these mechanisms.

A still further object is to provide means whereby the inking mechanism acting upon the planographic plates carried by the main 100 impression cylinder may be moved in its entirety toward or away from said cylinder, the cooperating mechanisms between said cylinder and said inking mechanism, whereby the latter is actuated, being so associated 105 and arranged as to be in the proper oper-

ative position when the inking mechanism is brought into operative relation with said main cylinder.

A still further object is to provide means, 5 adapted to be set by hand, to utilize the power being applied to the press to throw the two impression cylinders out of the impression position as to each other, or to restore them to such impression position.

10 A still further object is to provide a throw-off mechanism for the impression cylinders which will operate simultaneously, accurately and similarly upon both sides of one of said cylinders to move it out of the 15 impression relation to the other and preserve the proper alinement of the two cylinders.

A still further object is to so construct and arrange the automatically acting means 20 throwing the planographic or transfer cylinders out of the impression relation to the main cylinder, as to secure a parallel movement thereof, and preserve the alinement between the said planographic or transfer cylinders and the main impression cylinder.

25 A still further object is to provide a press of this character embodying automatically shiftable planographic damping and inking mechanisms, wherein the various damping and inking mechanisms will, after they have been shifted with relation to the planographic surfaces, be automatically restored to their former position when the shifting member ceases to be operative.

30 A still further object is to provide a press of this character wherein the impression upon the printing surfaces of the oppositely disposed impression cylinders will have such a relation as to properly register upon opposite sides of the printed sheet, through the impression upon one cylinder being transferred to the other cylinder by planographic plates carried by said first named cylinder.

35 A still further object is to provide adjusting means upon each of these planographic cylinders transferring an impression to the impression surface of the main cylinder, whereby the plates upon said planographic cylinders may be brought to register with each other in a manner to permit a plurality of superposed colors, in accurate register, to be transferred to the impression surface of said main cylinder.

40 A still further object is to provide adjusting means whereby the degree of pressure between the impression cylinders may be regulated to a nicety and the adjustment will remain undisturbed irrespective of the actuation of the mechanism for throwing said cylinders into and out of the impression relation. And a still further object is to provide in a machine of this character, actuating means controlling the various planographic cylinders and inking mechanisms, 45 the operation of which will be so synchro-

nized as to avoid interference between the various planographic cylinders, and between the inking mechanism acting upon the planographic plates upon the main impression cylinder, and the impression, or resilient, surface upon the said main cylinder. 70

The invention consists primarily in a printing machine, embodying therein a main impression cylinder carrying an impression surface adapted to receive an imprint 75 from a planographic plate, and planographic plates diametrically opposite said impression surface, a planographic transfer cylinder, a damping and inking mechanism therefor adapted to transfer an impression 80 to the impression surface upon said main cylinder, a damping and inking mechanism adapted to co-operate with the planographic plates upon said main cylinder, an impression cylinder oppositely disposed to said 85 main cylinder, and means automatically shifting said planographic cylinder and said damping and inking mechanisms acting upon the planographic plates upon said main cylinder whereby said planographic 90 cylinder and said damping and inking mechanisms are respectively made inoperative during each rotation of the main cylinder so as to afford clearance for the planographic plates upon the main cylinder, and 95 the impression surface thereon respectively; and in such other novel features of construction and combination of parts as are herein-after set forth and described, and more particularly pointed out in the claims hereto 100 appended.

Referring to the drawings:—Figure 1 is a side elevation of a machine embodying my invention; Fig. 2 is an elevation of the delivery end thereof; Fig. 3 is an elevation 105 of the feeding end thereof; Fig. 4 is a detail view of one planographic-plate cylinder and the parts appurtenant thereto; Fig. 5 is a detail view of the mechanism for throwing the main impression cylinder and the 110 oppositely disposed impression cylinder into and out of the impression relation; Fig. 6 is a diagrammatic view showing the position of parts just after an impression has been taken; Fig. 7 is a diagrammatic view showing the position of parts during the transfer 115 from the planographic cylinders to the impression surface upon the main impression cylinder, and the inking of the planographic plate prior to the transfer of the impression 120 to the oppositely disposed impression cylinder; Fig. 8 is a detailed perspective view illustrating the gripper mechanism used in connection with the oppositely disposed impression cylinders; Fig. 9 is a detail view 125 of the actuating mechanism for shifting the damping and inking mechanisms for preparing the planographic surfaces upon the main impression cylinder; Fig. 10 is a detail view showing the mechanism used for 130

varying the pressure between the two impression cylinders and between the planographic cylinders and the main impression cylinder; Fig. 11 is a detail view of one of the eccentric boxes for the planographic cylinders or the multi-revolution impression cylinder; and Fig. 12 is a detail view of one of the pressure regulating mechanisms.

Like reference numerals refer to like parts 10 throughout the several views.

In the embodiment of my invention shown in the drawings, 1 indicates the main frame of the machine, 2 the feeding shelf, 3 the collecting mechanism, which constitutes no 15 part of this invention and will not therefore be described in detail, and 4, the main power shaft. Mounted in fixed bearings in the main frame is the main impression cylinder 5, and oppositely disposed thereto is a second impression cylinder 6, of one half the diameter of the main impression cylinder, so as to cause said oppositely disposed cylinder 6 to turn two revolutions to each revolution of the main cylinder. These cylinders 20 are geared together so that one is driven from the other, and power is applied thereto by the main shaft 4 to continuously rotate both said cylinders when the press is in operation.

A machine made in accordance with my invention has the primary characteristic of being capable of use for simultaneously printing upon both sides of a sheet of paper, or being used as a perfecting press, and 30 has the secondary characteristics that it may be used to print upon either side of a sheet of paper and may print upon one side with a plurality of colors or with a single color.

To impart to the machine the characteristics above referred to, I have adopted a design wherein one of the impression cylinders is a multi-revolution cylinder, and the other cylinder has the twofold function of acting with the multi-revolution cylinder 45 as an impression cylinder during a portion of the rotation thereof, and prior to its so acting, transferring to said multi-revolution cylinder the impression from which the imprint is taken.

The main cylinder 5 has secured thereto in any desired manner to secure the desired tautness, a resilient printing and impression surface 7, extending throughout a portion of the periphery of said cylinder only, 55 and the impression cylinder 6 is provided with a similar printing and impression surface 8, said surfaces 7 and 8 corresponding as to length so as to act with each other, when taking the impression, to the full 60 length thereof. These surfaces 7 and 8 are similar in all respects to the ordinary printing surfaces of offset presses, excepting in such minor details which adapt them to this particular type of press. Any desired tensioning means may be employed for secur-

ing the necessary smoothness of said surfaces.

Diametrically opposite the surface 7 upon the main cylinder 5, I provide means whereby one or more planographic plates 9 may be secured upon said main cylinder, the surface of said plates 9 and of the impression surface 7 upon said cylinder being of the same height so that said plates and said surface will successively transfer an impression to the printing and impression surface 8 upon said cylinder 6 and come into the proper impression relation thereto with each single rotation of the main cylinder and each double rotation of the cylinder 6.

Mounted in the frame 1 upon one side of the main impression cylinder 5 is a plurality of cylinders 10 and 11, adapted to have secured thereto planographic plates which transfer to the printing and impression surface 7 upon said main cylinder, the design to be printed upon one side of the sheet of paper, two such cylinders being used in order to permit different colors to be superimposed upon said printing surface in order 90 that the design may be reproduced simultaneously in two colors. While a plurality of such planographic cylinders is desirable, only one such cylinder need be used if desired, and, as will hereinafter appear, I 95 have so constructed my machine that either of said cylinders may be thrown out of the transfer relation to the main cylinder so as to permit the other to occupy the operative relation thereto alone, for printing in a single color.

Each of the cylinders 10 and 11 and the parts appurtenant thereto are substantially the same, and I will therefore describe but one of these cylinders and its related mechanisms.

Each of the cylinders 10 and 11 is driven continuously from a gear carried by the main cylinder 5, so that with each rotation of said cylinder there will be two complete 110 rotations of said planographic cylinders, said cylinders being one-half the diameter of said main cylinder. Associated with each cylinder is a damping mechanism 12-13 adapted to moisten those parts of the plates 115 upon said cylinders which have an affinity for water so as to limit the distribution of the ink to those parts from which it is desired to print. The detailed construction of said damping mechanism is immaterial to my invention, the construction, uses and mode of operation thereof being old and well known in this and analogous arts. Such being the case, I will not enter into a detailed description of this mechanism excepting 120 in so far as it is related to the operation of the planographic cylinders while the machine is running. Also associated with each cylinder 10 and 11 is an inking mechanism 125 14-15 adapted to apply ink to the surface 130

of the plates upon each cylinder after the same have been damped, the plates upon said cylinders receiving during each rotation of the press two inkings. The inking mechanism of this character being used and well known in this and analogous arts, a description thereof will not be entered into, any desired or approved type of ink feeding, spreading and distributing rollers being applicable to a machine made in accordance with my invention. Associated with the main impression cylinder 5, on the side thereof opposite to the said planographic cylinders, is a damping mechanism 16, adapted to dampen the surface of the planographic plates 9 carried by said cylinder 5, and an inking mechanism 17, adapted to apply ink to said plates after they have been moistened by the said damping mechanism 16. It will thus be observed that each planographic cylinder and the planographic plates upon the main cylinder are provided with an individual damping and inking mechanism adapted, respectively, to prepare the plates upon said planographic or transfer cylinders and upon said main cylinder respectively, so as to transfer with each rotation of said main cylinder, the designs upon said plates to the impression and printing surface upon the main cylinder 5, and upon the corresponding surface of the multi-revolution cylinder 6.

Inasmuch as the plates 9 and the impression or printing surface 7 are of the same height, it is necessary to provide means whereby the planographic cylinders 10 and 11 will not interfere with the planographic surface upon the main cylinder and also to provide means whereby the damping and inking mechanisms for the plates 9 will not interfere with the impression transferred to the impression and printing surface 7, and that the actuation of this mechanism must be synchronized with the rotation of the main cylinder in a manner to throw the planographic cylinders into and out of the transfer relation to the planographic plates upon the main cylinder, and throw the damping and inking mechanism 50 into and out of the operative relation to the plates 9 upon said main cylinder, through the action of said main cylinder and with a timely movement, to insure the proper transfer of the design from said planographic cylinders and the proper damping and inking of said plates upon the main cylinder.

The quantity of movement of the various parts above referred to, to throw them into and out of the operative relation is comparatively small, a sixteenth of an inch being sufficient to secure perfect work by the machine.

The shifting mechanism for the cylinders 10 and 11 is the same, although the initiation of this movement occurs at different in-

tervals. I will therefore describe only one of these mechanisms and will refer to the others merely by reference numerals.

The shaft of each planographic cylinder is mounted in a bushing 18-19 having an eccentric outer surface, and carried by said bushing is a face plate 20-21 by means of which said bushing may be turned to force the cylinders 10 and 11 into and out of the transfer relation to the impression or printing surface upon the main cylinder. Each plate 20 21 is provided with a guide slot 22 23 for limiting its movement, and is connected by a link 24 25 with the short arm 26 27 of a bell crank lever, the plate 20 21 having a radially extending arm to which the link 24 25 is connected. The said bell crank lever is mounted upon a shaft 28 29 extending transversely of the machine, from side to side thereof, and the long arm 30 31 of said lever carries an anti-friction roller which is adapted to engage a cam 32 upon the shaft of the main impression cylinder 5, said cam 32 rotating with said main cylinder. Acting upon the shafts 28 and 29 respectively are torsion springs 33 34, which serve to normally turn said shafts in a manner to turn the bushings 18 19 to force the cylinders 10 and 11 into engagement with the main cylinder 5. As the bushings are turned through the lever system above referred to, such movement is against the tension of the springs 33 34 so that when the cam 32 ceases to be operative, said springs will instantly restore said planographic or transfer cylinders to their former operative position relative to the cylinder 5.

To insure substantially uniform constant pressure of the damping mechanism 12 13 upon the planographic or transfer cylinders 10 and 11, the rollers of these mechanisms are mounted in reciprocating side frames 35 and 36 having a yoke bearing upon the eccentric bushings 18 and 19 so that the actuation of said bushings in moving said planographic or transfer cylinders away from the main cylinder 5 will also impart a sufficient movement of the damping rollers to preserve their relation with their planographic or transfer cylinder. The requisite pressure of the damping rollers upon the planographic or transfer cylinders and the restoration of these parts to normal as the planographic or transfer cylinder reengages the main cylinder 5, is secured by means of a spring 37 38 acting upon a bell crank lever 39 40, one arm of which is pivotally connected to the frame 35 36. It will thus be observed that the damping mechanism is moved simultaneously with the movement of the planographic cylinder and in the same direction through the same agency and against the tension of the springs 37 38 which constantly tend to preserve the proper relation at all times.

times between the damping mechanisms and the planographic or transfer cylinders 10 and 11.

The movement of the planographic or transfer rollers 10 and 11 is so slight as not to require a movement of the inking mechanism, the rollers of said inking mechanism being sufficiently resilient to permit this movement without affecting the efficiency of said mechanism. The distributing rollers of each inking mechanism 14 and 15, however, are mounted in an adjustable frame 41 42 having a projecting arm 43 44 connected by a link 45 46 with a bell crank actuating lever 47 and 48 so that either or both of said inking mechanisms may be thrown out of the inking relation to its planographic or transfer cylinder. Connecting the long arm of the operating levers 47 and 48 so as to be detachable therefrom, is a connecting link 49 which permits both inking mechanisms to be simultaneously actuated through either operating handle 47 48.

I have not described the driving mechanisms for the various rollers constituting the inking and damping mechanisms, as these are mere matters of mechanical detail and within the province of the skilled mechanic.

Carried by the shaft of the main impression cylinder 5 is a second cam 50, the rise of which is upon that side of the cylinder which carries the rubber impression surface and is of an arc of a length corresponding in degree with the arc of the said impression or printing surface. Mounted upon the frame of the machine adjacent to said cam is a plurality of slides 51 52 53, the ends of which adjacent to said cam carry anti-friction rollers and the other ends of which project in a manner to engage the various mechanisms actuated thereby. Said cam is for the purpose of accomplishing that displacement of the damping and inking mechanism acting upon the main impression cylinder in the manner above referred to to make said mechanisms inoperative as to the rubber printing or impression surface. The arrangement described permits the actuation of the damping and inking mechanisms in sequence, while at the same time holding both of these mechanisms out of the operative relation to the main impression cylinder at that interval in which the resilient printing or impression surface is within the operative range of both the damping and the inking mechanism. To adapt the said damping and inking mechanism to the particular structure of the machine, it is essential to construct them with relation to the coöperating mechanisms, which construction however, has no relation to the manner in which these mechanisms operate in moistening or inking the planographic plates. The entire damping mechanism 16

is carried by an oscillatory frame 54, pivoted at 55 and supported by a spring 56 provided with a tensioning mechanism 57. The spring 56 normally supports the damping mechanism and forces it into the desired intimate relation to the plate upon the main impression cylinder 5. Said frame is provided with a bearing 58 adapted to receive the thrust of the slide 51, thus causing the outward movement of said slide to displace the entire damping mechanism and hold it out of the operative damping relation to the main cylinder 5 as long as said slide is under the control of the rise of the cam 50. As the said slide leaves said rise, 80 the spring 56 will restore the damping mechanism to its normal position, thus at all times holding the roller upon the slide 51 against the cam 50 and causing it to follow said cam.

The distributing rollers of the inking mechanism 17 are carried by independent oscillatory side plates 59 and 60 pivoted together at 61 to secure a lazy tongs lever arrangement. The arms of these levers bear against slides 52 53 and are forced into this relation by the spring 62. It will thus be observed that the levers 59 and 60 are opened by the application of power thereto through the slides 52 and 53 successively and 95 the cam 50, and that as opened, the spring 62 will be so tensioned as to automatically restore these parts to their former operative relation immediately that the slides 52 and 53 pass from the rise of the cam 50, these 100 slides being caused to follow said cam by the spring 62.

The entire inking mechanism 17 is mounted upon a sliding carriage 63 actuated by a rack and pinion mechanism 64, said carriage 105 being capable of being reciprocated in the manner indicated in dotted lines in Fig. 1 to remove the entire inking mechanism from its position adjacent to the main cylinder 5 and permit access to said cylinder for the 110 purpose of applying and removing the plates thereto and therefrom. While running, the said carriage is held in the proper relation to the said cylinder by the latch member 65.

To permit either or both of the planographic cylinders 10 and 11 to be thrown out of the operative relation to the main cylinder 5, I provide means rendering the springs 37 and 38 inoperative to restore said cylinders to their operative position after they have been displaced through the action of the cam 32. In practice, I preferably provide each cylinder with an independently operative cut out mechanism so constructed 120 and arranged as to permit the movement of said planographic cylinders under the power of the machine, the cut out mechanism acting merely to prevent the restoration of these parts to normal under 130

their springs 37 and 38. Carried by the collar of the bell crank lever 26-27 respectively, is a ratchet tooth 66-67 and mounted upon the frame of the machine adjacent thereto is a counterweighted oscillatory dog 68-69 which dog when thrown in one direction will be out of engagement with the tooth 66-67 and permit the free oscillatory movement of the shaft 28-29, and when thrown in the opposite direction will, through the counterweight carried thereby, be caused to drop into engagement with the said ratchet tooth 66-67 as the shafts 28-29 reach the limit of their oscillatory movement under the control of the cam 32. By means of the independent cut out mechanism for each planographic or transfer cylinder 10 or 11, the press may be adjusted to print upon one side of the sheet in either one or two colors, or the sheet may be caused to receive an impression from the multi-revolution cylinder only.

In presses of this character, it is desirable to regulate to a nicety the degree of pressure between the planographic or transfer cylinders, as well as between the cylinders of the printing couple, to secure a sharp imprint. The pressure between the planographic or transfer cylinders 10 and 11 and the printing surface 7 upon the main impression cylinder 5 results from the action of the springs 33-34 upon the shaft 28-29, the movement of said shaft being controlled by the plate 20-21 and the slot 22 and stud pin 23 in and acting upon said plate. To secure the desired variance in the relation of the cylinders 10 and 11 without disturbing the relation or adjustment of the parts through which the springs 33-34 act, I connect the link 24-25 with the plate 20-21 by means of an eccentric pivot 70-71 through which the eccentric bushing to which said plate is attached may be moved in either direction independently of said link 24-25, to vary the normal position of the planographic or transfer cylinders 10 and 11 relative to the main impression cylinder 5. By adjusting the cylinders in the manner referred to, through the two eccentrics, a micrometrical adjustment is possible.

While the press is running, the relation of the impression cylinders forming the printing couple is always the same, but to secure the proper degree of pressure between said members and at the same time permit the press to be thrown out of operation independently of the power, I provide means whereby the multi-revolution cylinder 6 may be thrown in and out of the impression relation to the main cylinder 5 at the will of the operator, thus permitting all of the mechanisms to be operative without making an imprint. To accomplish this result, I mount the arbor of the multi-revolution cylinder 6 in an eccen-

tric bushing 72, mounted in the frame of the machine; and provided with a face plate 73 having an extension 74 thereon and having a slot 75 inclosing a stop pin carried by the frame of the machine. Mounted adjacent to said cylinder 6 is a crank shaft 76, one crank of which is connected by a link 77 with the extension 74 upon the plate 73. The crank shaft 76 carries a second crank 78 to which is pivotally connected a link 79, the lower end of which terminates in an elliptical, closed loop 80 adjacent to the end of the shaft of the main impression cylinder 5. Upon the inner periphery of the loop 80 is a plurality of oppositely disposed projections 81 and 82, either of which is adapted to be engaged by a tappet 83 upon the shaft of the said cylinder when the loop is thrown into such a position as to bring either of said projections within the line of motion of the said tappet. Means are provided for oscillating the link 79 to position it so as to cause the tappet to act upon either of said projections as required, which means preferably consist of a crank 84 mounted within the link 79 and carrying a plate 85 having attached thereto eccentrically thereof a rod 86 passing through a bearing 87 upon the frame of the machine and having acting thereon the springs 88 and 89 upon opposite sides of the bearing 87. The spring 88 acts to normally position the plate 85 and crank shaft 84 so as to hold the projections 81 and 82 out of the path of the tappet 83, while the cylinders are out of the impression relation; and after the said link has been actuated to so throw them out of this relation; while the spring 89 acts as a resistance the reaction from which will throw the link 79 and its loop 80 toward the tappet 83 to cause said tappet to engage the lever handle projection carried by said loop and force it downwardly to bring the two members of the printing couple into the desired impression relation.

To secure the regulation of the pressure between the two members of the printing couple, I connect the link 77 with the plate by means of an eccentric pivot 90, similar in design and mode of operation to the eccentric pivots 70 and 71, thus permitting the plate and its eccentric bushing to be shifted in a manner to move said cylinder either away from or toward the main impression cylinder 5. This regulating mechanism is substantially the same as that shown and described in connection with the planographic or transfer cylinders 10 and 11, and the use of the eccentric 90 acting upon the other 72, permits the same micrometrical adjustment of the multi-revolution cylinder 6 with relation to its planographic plates 9 upon the main cylinder 5, and the impression surface 7 upon said cylinder, as that in connection with the planographic cylinders 10 and 11,

and the impression surface upon said main cylinder.

As above stated, the impression cylinder 6 makes two revolutions to each revolution of the main impression cylinder 5, the first revolution being for the purpose of effecting the transfer thereto of the impression from the planographic plates 9 upon the main cylinder. Upon the second revolution, the imprint is made; and between the completion of the first and of the second revolutions, the feeding of the paper to the cylinder is accomplished. To secure a timely feeding of the sheets of paper, the feeding mechanism 2 is employed and the cylinder 6 is provided with gripper fingers 91 which automatically close with the initiation of the second revolution of the cylinder, and automatically open toward the completion of this revolution. This gripper mechanism includes therein a disk 92 having therein a diametrical slot 93 adapted to receive pins 94 and 95 mounted upon the frame of the machine and actuated by the levers 96 and 97 from a worm gear 98 carried by the shaft of the main impression cylinder 5. Said levers 96 and 97 receive a timely reciprocation from said worm 98 so as to impart to the pins 94 and 95 timely movement to secure the closing of the gripper fingers 91 upon the forward edge of the sheet of paper as it is fed to said grippers upon the initiation of the second revolution of the impression cylinder 6, and a timely opening of said fingers as it approaches the end of said revolution, so as to insure the delivery of the printed sheet through the delivery mechanism 3.

The operation of the herein described printing machine is substantially as follows:—Normally, even while power is being applied to the main shaft 4, the members 5 and 6 of the printing couple will be out of the impression relation through the elevation of the member 6 by the eccentric 72. The various planographic plates having been properly inked, and the press being in condition to make a run, the impression cylinders 5 and 6 are brought into the printing relation by throwing the lever 84 to the left. As the lever is thus thrown, the reaction from the spring 89 throws the link 79 to the right, (see Fig. 5) bringing the projection 81 within the line of movement of the tappet 83. With the next rotation of the main cylinder 5, this tappet engages said projection, forcing the link 79 downwardly to an extent to clear said projection and continue its rotation without further engagement therewith. As the link 79 is thus drawn downwardly, it oscillates the crank shaft 76 and through the link 77, the plate 73 carrying the eccentric bushing 72. This eccentric is so set that with this rotary movement the arbors of the cylinder 6 will be lowered, thus

bringing the resilient impression surface 8 upon said cylinder into the plane of engagement with the plates 9 and impression surface 7 upon the main cylinder 5. The stresses upon this cylinder 6 are such that it will retain any position into which it is forced through the eccentric bushings of its arbors, the degree of pressure being determined by the set of the eccentric 72, and the position of this eccentric being capable of being varied without disturbing the relation or adjustment of the various parts actuating same by means of the eccentric pivot 90, connecting the link 77 with the plate 73. Any desired locking means may be employed for holding the pivot 90 in any adjusted position. The adjustment of the impression cylinder 6 to vary the pressure will under all circumstances be very minute, and the employment of one eccentric to vary the position of the other, permits an adjustment sufficiently fine to meet the needs of a press having even those fine requirements as to pressure found in offset presses, wherein each printing surface acts both as an impression surface and a platen. If it be desired to throw the cylinders 5 and 6 out of the operative relation while the press is running, the crank handle 84 will be swung to the limit of its movement to the right, the spring 88 drawing the link 79 and its loop 80 to the left to an extent to bring the projection 82 on said loop within the line of movement of the tappet 83, thus causing this tappet with the next rotation of the main cylinder 5, to raise the link 79, thus reversing the movement of the eccentric bushing 72 to raise the cylinder 6 out of the printing position, this action being a mere reversal of that already described. As the link 79 is raised, the spring 89 will draw the crank handle 84 to its normal inoperative position as shown in Fig. 5. As the main cylinder 5 rotates, the resilient impression surface 7 thereon will receive from each of the plates upon the planographic cylinders 10 and 11 an imprint, these imprints being applied successively, in perfect register one with the other, so that the impression taken from this surface 7 will be in a plurality of colors. With each revolution of the main cylinder 5, the zinc or other planographic plates 9 thereon will be dampened and inked and brought into the printing or impression relation with the elastic printing or impression surface 8 upon the multi-revolution cylinder 6, so as to transfer the design thereon to said cylinder prior to the establishment of the printing relation between said cylinder 6 and the elastic printing surface 7 upon the cylinder 5. While a single color only is thus transferred to the printing surface 8, it will be observed that as the sheet passes between the rollers 5 and 6 it will receive imprints simultaneously upon both sides thereof, one side

130

of the sheet at least being printed in a plurality of colors.

It being essential in a press wherein one cylinder carries both a printing surface and a planographic plate, that the planographic or transfer cylinders impressing the design upon the printing surface upon the said cylinder, and the damping and inking mechanisms for preparing the planographic plates upon said cylinder, shall respectively be inoperative as to the planographic plates and as to said printing surface upon said cylinder. In securing this result, the cams 32 and 50 are provided upon the shaft of the cylinder 5, these cams with each rotation of said cylinder acting respectively to shift the planographic cylinders out of the operative relation to said main cylinder while the planographic plates 9 are in a position where they would otherwise be engaged by said planographic cylinders or the plates thereon, and shifting the damping and inking mechanisms 16 and 17 when the printing surface 7 is in a position relative thereto where it would otherwise receive moisture and ink from said last named mechanisms. As the cam 32 rotates with the cylinder 5, it successively engages the arms 30-31 and therethrough rocks the shafts 28 and 29 against the tension of the torsion springs 33 and 34. This movement of said shafts through the links 24 and 25 respectively oscillates the plates 20 and 21 and with them the eccentric bushings 18 and 19 carrying the arbors of the cylinders 10 and 11. These bushings are so set that the movement of the cylinders 10 and 11 will be radially of the main cylinder 5 and the degree of movement will be constant and merely sufficient to bring the planographic surfaces upon said cylinders out of the operative relation to the plates 9 upon said main cylinder. If it be desired to vary the pressure of the plates upon the cylinders 10 and 11 relative to the printing or impression surface upon the cylinder 5, the eccentric bushings 18 and 19 may be shifted in their position through the plates 20 and 21 by means of the eccentric pivots 70 and 71 connecting said plates to the links 24 and 25 respectively. Upon the disengagement of the cam 32 from the arms 30 and 31, the springs 33 and 34 will instantly restore, through the same mechanism used for shifting same, the planographic cylinders 10 and 11 to their former operative position, this return movement being so timed through the lay out of the cam 32 to position them preparatory to their engagement with the printing surface 7 upon the main cylinder 5. As the planographic cylinders 10 and 11 are thus shifted, the frames 35 and 36 carrying the damping rollers will be shifted to the same extent, through the movement of said cylinders 10 and 11, thus always maintaining said damp-

ing mechanism in the same position relative to the plates upon said cylinders. The movement of the said frames 35 and 36 is against the tension of the springs 37 and 38 developed by the bell crank levers 39 and 40, so that with the automatic restoration of the cylinders 10 and 11 to their normal operative position under the springs 33 and 34, the damping mechanism will also be automatically restored to its former normal position through the springs 37 and 38. The tension of said springs being adjustable, the damping mechanism may be maintained in the proper relation to the planographic or transfer cylinders at all times and the movement thereof may be synchronized with that of the said planographic or transfer cylinders to secure the maintenance of a proper relative position of these parts at all times.

As stated above, the resiliency of the inking rollers and the small quantity of movement of the planographic or transfer cylinders makes it unnecessary to provide an automatic shift mechanism for said inking mechanism.

The gears driving the cylinders of the printing couple and driving the planographic or transfer cylinders 10 and 11 from the gear upon the main cylinder are always in mesh, so that the plates upon the said cylinders 10 and 11 receive two dampenings and two inkings with each impression taken therefrom.

The cam 32 is set upon the shaft of the main impression cylinder 5, in a position so as to be operative throughout an arc corresponding with the arc of the planographic plates carried upon said cylinder, both planographic cylinders being inoperative during the entire period within which the planographic plates 9 are passing said cylinders 10 and 11.

If it be desired to print upon the under side of the sheet in only one color, or not to print upon the under side of the sheet at all, either cylinder 10 or 11 may be cut out by merely throwing the pawl 68 or 69 into position where it will engage the ratchet tooth 66 or 67 upon the collar of the lever 26 or 27, as said lever reaches its maximum throw under the cam 32, thus preventing a return movement of these levers, and of the cylinders 10 and 11, or either of them, to the normal operative position. At the same time, either inking mechanism may be thrown out of engagement with the plates on this cylinder by means of the levers 47 and 48 and the lever mechanism connecting said levers with the frames carrying said inking mechanisms or by using the connecting link 49, both inking mechanisms may be simultaneously thrown out of the inking relation.

While the planographic or transfer cylinders 10 and 11 are being shifted in the man-

ner above referred to, the damping mechanism 16 and inking mechanism 17 will also be shifted so as to provide the proper clearance for the elastic impression or printing 5 surface 7 upon the main cylinder 5, which surface has been previously inked by the plates upon said cylinders 10 and 11. This shifting of the said damping and inking mechanisms results from the engagement of 10 the cam 50 with the slides 51, 52 and 53 successively, which slides, engaging the frames 54 and the levers, and the frames terminating in the lazy tongs levers 59 and 60, force the said frames 54, 59 and 60 away 15 from the cylinder 5, carrying with them the damping and inking rollers. The movement of the frame 54 is against the tension of the spring 56, so that immediately after the slide 51 leaves the cam 50, said spring will 20 restore said damping mechanism to its former normal position. The movement of the lazy tongs frame of the inking mechanism is against the tension of the spring 62, with the result that this spring restores the inking 25 rollers to their normal position immediately upon the disengagement of the slides 52 and 53 from said cam. By this construction it will be observed that with each rotation of the main cylinder 5, the plates 9 30 thereon receive one dampening and a double inking, there being a double set of inking rollers in the inking mechanism 17. The movable frame 63 is used to permit access to the cylinder 65 for the purpose of adjusting the plates thereon and this frame may be utilized to throw the inking mechanism 17 in its entirety out of the operative 35 position and thus permit the press to print upon the under side of the sheet only, in 40 either one or two colors, as desired. When the frame 63 is thus thrown out of position relative to the printing couple, the cam 50 will operate upon the slides 51, 52 and 53 without affecting the mode of operation of 45 press in any way, while when the frame 63 is brought into its operative position, these slides will be automatically coupled or connected therewith by an impact coupling, thus affording means whereby the frame 63 50 may be shifted without the necessity for readjusting any of the operative parts of the machine. In other words, the mere forcing of the frame 63 into the proper relation to the printing couple automatically couples 55 the elements affecting the desired mode of operation of said inking mechanism. It will thus be observed that when the cams 32 and 50 are inoperative, the planographic or transfer plates 9 upon the cylinder 5 will be 60 undergoing the process of being dampened and inked, while the plates upon the planographic cylinders 10 and 11 will be transferring the impression to the elastic impression or printing surface upon said cylinder, 65 both said planographic cylinders and said

damping and inking mechanisms being operative at the same time, as shown in Fig. 7. When both the cams 32 and 50 are operative, however, said cylinders and said inking mechanism will be shifted out of the operative relation to the main cylinder 5, in the manner shown in Fig. 6. The impression or printing surface 9 having received its imprint in the manner described, and the plates 9 having been dampened and inked as described, with the rotation of the cylinder 5 the design upon the plates 9 will be transferred to the printing or impression surface 8 upon the cylinder 6, which will describe one complete revolution when receiving said impression. Upon the second revolution of said cylinder 6 it will be in the operative relation to the printing or impression surface 7 upon the main cylinder 5 and the said impression surfaces 7 and 8 will act against each other to simultaneously print upon both sides of the sheet, one printing surface acting as a platen to the other as well as acting as a printing surface. 90

The operation of the fingers 91 in feeding the paper between the cylinders 5 and 6 has been referred to above, the lay out of the worm 98 being such as to impart timely movement to the levers 96 and 97, controlling the pins 94 and 95, so as to thrust them into the slot 93 in the disk 92. The point of engagement of said pins in said slot being adjacent to the periphery of the disk, the continued rotation of the disk with the cylinder 6 will result in substantially a quarter revolution of said disk and a corresponding movement of the fingers. 95

The sheet feeding and delivery mechanisms and the mode of operation thereof are immaterial to this invention, it being apparent that any such mechanisms may be employed in connection with the printing couple and mechanisms appurtenant thereto, for applying the design to the planographic printing surfaces thereof, and to vary the adjustment of the members of the printing couple and these appurtenances. 100

It is not my intention to limit the invention to the precise details of construction shewn in the drawings, although such have been found highly efficient in use. 105

Having described my invention, what I claim as new and desire to have protected by Letters Patent, is:—

1. A printing-machine, embodying therein a main impression cylinder, carrying an impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an im- 115

pression to the impression surface upon said main cylinder, a damping and an inking mechanism adapted to coöperate with the planographic plate upon said main cylinder,

5 an impression cylinder oppositely disposed to said main cylinder, and means automatically shifting said planographic or transfer cylinder, and said damping and inking mechanisms coöperating with the planographic

10 plate upon said main cylinder, whereby said planographic cylinder and said damping and inking mechanisms are respectively made inoperative during each rotation of the main cylinder to afford clearance for the

15 planographic plate upon the main cylinder and the impression surface thereon respectively.

2. A printing machine, embodying therein a main impression cylinder carrying an elastic impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an impression to the impression surface upon said main cylinder, a damping and an inking

25 mechanism adapted to coöperate with the planographic plate upon said main cylinder, an impression cylinder, having an elastic printing surface, oppositely disposed to said main cylinder, and means automatically

30 shifting said planographic or transfer cylinder, and said damping and inking mechanisms coöperating with the planographic plate upon said main cylinder, whereby said planographic cylinder and said damping and inking mechanisms are respectively made inoperative during each

35 rotation of the main cylinder to afford clearance for the planographic plate upon the main cylinder and the impression surface thereon respectively, and means whereby the planographic cylinder may be held out of the operative relation to the main cylinder.

40

45

3. A printing machine, embodying therein a main impression cylinder, carrying an impression surface adapted to receive a planographic plate diametrically opposite said impression surface, a plurality of planographic or transfer cylinders, a damping and an inking mechanism for each of said cylinders, the plates upon said planographic or transfer cylinders being adapted to transfer an impression to the impression surface upon said main cylinder, a damping and an inking mechanism adapted to coöperate with the planographic plate upon said main cylinder, an impression cylinder oppositely disposed to said main cylinder, and means automatically shifting said planographic or transfer cylinders, and said damping and inking mechanisms coöperating with the planographic plate upon said main cylinder,

55 whereby said planographic cylinders and said damping and inking mechanisms are respectively made inoperative during each rotation of the main cylinder to afford clearance for the planographic plate upon the main cylinder and the impression surface thereon respectively, and independently operative means whereby either or both planographic cylinders may be held out of the operative relation to the main impression cylinder.

60

65

said damping and inking mechanisms are respectively made inoperative during each rotation of the main cylinder to afford clearance for the planographic plate upon the main cylinder and the impression surface thereon respectively.

4. A printing machine, embodying therein a main impression cylinder, carrying an impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an impression to the impression surface upon said main cylinder, a damping and an inking mechanism adapted to coöperate with the planographic plate upon said main cylinder, an impression cylinder oppositely disposed to said main cylinder, and means automatically shifting said planographic or transfer cylinder, and said damping and inking mechanisms coöperating with the planographic plate upon said main cylinder, whereby said planographic cylinder and said damping and inking mechanisms are respectively made inoperative during each

75 rotation of the main cylinder to afford clearance for the planographic plate upon the main cylinder and the impression surface thereon respectively, and means whereby the planographic cylinder may be held out of the operative relation to the main cylinder.

80

5. A printing machine, embodying therein a main impression cylinder, carrying an impression surface adapted to receive a planographic plate diametrically opposite said impression surface, a plurality of planographic or transfer cylinders, a damping and an inking mechanism for each of said cylinders, the plates upon said planographic or transfer cylinders being adapted to transfer an impression to the impression surface upon said main cylinder, a damping and an inking mechanism adapted to coöperate with the planographic plate upon said main cylinder, an impression cylinder oppositely disposed to said main cylinder, means automatically shifting said planographic or transfer cylinders, and said damping and inking mechanisms coöperating with the planographic plate upon said main cylinder,

95 whereby said planographic cylinders and said damping and inking mechanisms are respectively made inoperative during each rotation of the main cylinder to afford clearance for the planographic plate upon the main cylinder and the impression surface thereon respectively, and independently operative means whereby either or both planographic cylinders may be held out of the operative relation to the main impression cylinder.

6. A printing machine, embodying there-in a main impression cylinder, carrying an impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an impression to the impression surface upon said main cylinder, a damping and an inking mechanism adapted to co-operate with the planographic plate upon said main cylinder, an impression cylinder oppositely disposed to said main cylinder, means developing pressure between said main cylinder and said oppositely disposed cylinder, means whereby the degree of such pressure may be regulated, and means automatically shifting said planographic or transfer cylinder, and said damping and inking mechanisms co-operating with the planographic plate upon said main cylinder, whereby said planographic cylinder and said damping and inking mechanisms are respectively made inoperative during each rotation of the main cylinder to afford clearance for the planographic plate upon the main cylinder and the impression surface thereon respectively. 70
7. A printing machine, embodying there-in a main impression cylinder, carrying an impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an impression to the impression surface upon said main cylinder, means adapted to press said planographic cylinder upon said main impression cylinder, means whereby the degree of such pressure may be regulated, a damping and an inking mechanism adapted to co-operate with the planographic plate upon said main cylinder, an impression cylinder oppositely disposed to said main cylinder, and means automatically shifting said planographic or transfer cylinder, and said damping and inking mechanisms co-operating with the planographic plate upon said main cylinder, whereby said planographic cylinder and said damping and inking mechanisms are respectively made inoperative during each rotation of the main cylinder to afford clearance for the planographic plate upon the main cylinder and the impression surface thereon respectively. 75
8. A printing machine, embodying there-in a main impression cylinder, carrying an impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an impression to the impression surface upon said main cylinder, a damping and an inking mechanism adapted to co-operate with the planographic plate upon said main cylinder, an impression cylinder oppositely disposed to said main cylinder, means developing pressure between said main cylinder and said oppositely disposed cylinder, means whereby the degree of such pressure may be regulated, and means automatically shifting said planographic or transfer cylinder, and said damping and inking mechanisms co-operating with the planographic plate upon said main cylinder, whereby said planographic cylinder and said damping and inking mechanisms are respectively made inoperative during each rotation of the main cylinder to afford clearance for the planographic plate upon the main cylinder and the impression surface thereon respectively. 80
9. A printing machine, embodying there-in a main impression cylinder, carrying an impression surface adapted to receive an imprint from a planographic plate, and adapted to receive a planographic plate diametrically opposite said impression surface, a planographic or transfer cylinder, a damping and an inking mechanism therefor, the plate upon said planographic or transfer cylinder being adapted to transfer an impression to the impression surface upon said main cylinder, means adapted to press said planographic cylinder upon said main impression cylinder, means whereby the degree of such pressure may be regulated, a damping and an inking mechanism adapted to co-operate with the planographic plate upon said main cylinder, an impression cylinder oppositely disposed to said main cylinder, and means developing pressure between said main cylinder and said oppositely disposed cylinder, means whereby the degree of such pressure may be regulated, and means automatically shifting said planographic or transfer cylinder, and said damping and inking mechanisms co-operating with the planographic plate upon said main cylinder, whereby said planographic cylinder and said damping and inking mechanisms are respectively made inoperative during each rotation of the main cylinder to afford clearance for the planographic plate upon the main cylinder and the impression surface thereon respectively. 85
10. A printing machine, embodying there-in a printing couple comprising a main cylinder having a printing and impression surface on one portion thereof and means whereby a planographic plate may be attached to another portion thereof, and an oppositely disposed multi-revolution cylinder having an impression and printing sur- 90

face thereon, in combination with means for transferring a design to said printing and impression surface upon said main cylinder, and an inking mechanism for applying ink 5 directly to the plate upon said main cylinder.

11. A printing machine, embodying therein a printing couple comprising a main cylinder having an elastic printing and impression surface on one portion thereof and means whereby a planographic plate may be attached to another portion thereof, and an oppositely disposed multi-revolution cylinder having an elastic impression and printing surface thereon in combination with means for transferring a design to said printing and impression surface upon said main cylinder, and an inking mechanism for applying ink directly to the plate upon said 20 main cylinder.

12. A printing machine, embodying therein a printing couple comprising a main cylinder having a printing and impression surface on one portion thereof and means whereby a planographic plate may be attached to another portion thereof, an oppositely disposed multi-revolution cylinder having an impression and printing surface thereon, and means whereby said cylinders 25 may be thrown into and out of the printing relation in combination with means for transferring a design to said printing and impression surface upon said main cylinder, and an inking mechanism for applying ink 30 directly to the plate upon said main cylinder.

13. A printing machine, embodying therein a printing couple comprising a main cylinder having a printing and impression surface on one portion thereof and means whereby a planographic plate may be attached to another portion thereof, an oppositely disposed multi-revolution cylinder having an impression and printing surface 45 thereon, and means whereby the pressure between said cylinders may be regulated in combination with means for transferring a design to said printing and impression surface upon said main cylinder, and an inking mechanism for applying ink 50 directly to the plate upon said main cylinder.

14. A printing machine, embodying therein a printing couple comprising a main cylinder having a printing and impression surface on one portion thereof and means whereby a planographic plate may be attached to another portion thereof, an oppositely disposed multi-revolution cylinder having an impression and printing surface 55 thereon, and means whereby the pressure between said cylinders may be regulated, comprising means adapted to impart movement to one of said cylinders toward or from the other, and supplemental means actuating said last named means whereby a micromet-

rical adjustment is afforded in combination with means for transferring a design to said printing and impression surface upon said main cylinder, and an inking mechanism for applying ink directly to the plate upon said 70 main cylinder.

15. A printing machine, embodying therein a printing couple comprising a main cylinder having a printing and impression surface on one portion thereof, and means whereby a planographic plate may be attached to another portion thereof, an oppositely disposed multi-revolution cylinder having an impression and printing surface thereon, and means whereby said cylinders 75 may be thrown into and out of the printing relation, comprising eccentric bushings for said multi-revolution cylinder, and means whereby said bushings may be oscillated in combination with means for transferring a design to said printing and impression surface upon said main cylinder, and an inking mechanism for applying ink directly to the plate upon said main cylinder.

16. A printing machine, embodying therein a printing couple comprising a main cylinder having a printing and impression surface on one portion thereof, and means whereby a planographic plate may be attached to another portion thereof, an oppositely disposed multi-revolution cylinder having an impression and printing surface thereon and means adapted to be actuated through the power driving the press whereby said cylinders may be thrown into and 90 out of the printing relation, comprising eccentric bushings for said multi-revolution cylinder, and means whereby said bushings may be oscillated in combination with means for transferring a design to said printing and impression surface upon said main cylinder, and an inking mechanism for applying ink directly to the plate upon said main cylinder.

17. A printing machine, embodying therein a printing couple comprising a main cylinder having a printing and impression surface on one portion thereof, and means whereby a planographic plate may be attached to another portion thereof, an oppositely disposed multi-revolution cylinder having an impression and printing surface thereon, and means adapted to be actuated through the power driving the press whereby said cylinders may be thrown into and 95 out of the printing relation, comprising eccentric bushings for said multi-revolution cylinder, and means whereby said bushings may be oscillated, comprising a crank shaft, a link pivotally connected with a crank thereon and acting eccentrically of said bushings, and means whereby said shaft may be oscillated in both directions in combination with means for transferring a design to said printing and impression surface.

face upon said main cylinder, and an inking mechanism for applying ink directly to the plate upon said main cylinder.

18. A printing machine, embodying there-
in a printing couple comprising a main cyl-
inder having a printing and impression sur-
face on one portion thereof, and means
whereby a planographic plate may be at-
tached to another portion thereof, an oppo-
sitely disposed multi-revolution cylinder
having an impression and printing surface
thereon, and means adapted to be actuated
through the power driving the press where-
by said cylinders may be thrown into and
out of the printing relation, comprising
eccentric bushings for said multi-revolution
cylinder, and means whereby said bushings
may be oscillated, comprising a crank shaft,
a link pivotally connected with a crank
thereon and acting eccentrically of said
bushings, a link pivotally connected to a
second crank on said shaft, a loop on the
free end of said link, a plurality of oppo-
sitely disposed, inwardly extending projec-
tions on said loop, a tappet rotatable with
said main impression and printing cylinder,
and means whereby said loop may be ac-
tuated to cause said tappet to exert a down-
ward thrust upon one of said projections, or
an upward thrust upon the other to oscillate
said shaft, in combination with means for
transferring a design to said printing and
impression surface upon said main cylinder,
and an inking mechanism for applying ink
directly to the plate upon said cyl-
inder.

19. A printing machine, embodying there-
in a printing couple comprising a main cyl-
inder having a printing and impression sur-
face on one portion thereof, and means
whereby a planographic plate may be at-
tached to another portion thereof, an oppo-
sitely disposed multi-revolution cylinder
having an impression and printing surface
thereon, and means adapted to be actuated
through the power driving the press where-
by said cylinders may be thrown into and
out of the printing relation, comprising
eccentric bushings for said multi-revolution
cylinder, and means whereby said bushings
may be oscillated, comprising a crank shaft,
a link pivotally connected with a crank
thereon and acting eccentrically of said
bushings, a link pivotally connected to a
second crank on said shaft, a loop on the
free end of said link, a plurality of oppo-
sitely disposed, inwardly extending projec-
tions on said loop, a tappet rotatable with
said main impression and printing cylinder,
a crank carried by said last named link, a
rod, oppositely acting cushion springs act-
ing thereon, and a connection between said
rod and said last named crank whereby the
oscillation of said crank in one direction will
move its link in the opposite direction to

cause said tappet to exert a downward
thrust upon one of said projections, or an
upward thrust upon the other to oscillate
said shaft.

20. A printing machine, embodying there-
in a printing couple comprising a main cyl-
inder having a printing and impression sur-
face on one portion thereof and means
whereby a planographic plate may be at-
tached to another portion thereof, an oppo-
sitely disposed multi-revolution cylinder
having an impression and printing surface
thereon, and means whereby the pressure
between said cylinders may be regulated,
comprising means adapted to impart move-
ment to one of said cylinders toward or
from the other, and an eccentric actuating
said last named means whereby a micromet-
rical adjustment is afforded, in combination
with means for transferring a design to said
printing and impression surface upon said
main cylinder, and an inking mechanism for
applying ink directly to the plate upon said
main cylinder.

21. A printing machine, embodying there-
in a printing couple comprising a main cyl-
inder having a printing and impression sur-
face on one portion thereof, and means
whereby a planographic plate may be at-
tached to another portion thereof, an oppo-
sitely disposed multi-revolution cylinder
having an impression and printing surface
thereon, means, adapted to be actuated
through the power driving the press, where-
by said cylinders may be thrown into and
out of the printing relation, comprising
eccentric bushings for said multi-revolution
cylinder, and means whereby said bushings
may be oscillated, comprising a crank shaft,
a link pivotally connected with a crank
thereon and acting eccentrically of said
bushings, and means whereby said shaft may
be oscillated in both directions, and micro-
metrical adjusting means whereby the pres-
sure between said cylinders may be regu-
lated, comprising an eccentric pivot connect-
ing said link with said bushing whereby said
bushing may be oscillated independently of
the movement of said link.

22. A printing machine, embodying there-
in a main impression cylinder carrying a
printing and impression surface thereon,
and means whereby a planographic plate
may be attached thereto, a planographic
cylinder adapted to transfer an impression
to the printing and impression surface of
said main cylinder, eccentric bushings for
the arbors of said planographic cylinder,
means actuated from said main cylinder for
imparting an intermittent oscillatory move-
ment to said bushings, damping and inking
mechanisms for said planographic plate
upon said main cylinder, and means where-
by said last named damping and inking
mechanisms are thrown out of the operative

relation to said printing and impression surface upon said main cylinder.

23. A printing machine, embodying therein a main impression cylinder carrying a printing and impression surface thereon, and means whereby a planographic plate may be attached thereto, a planographic cylinder adapted to transfer an impression to the printing and impression surface of said main cylinder, eccentric bushings for the arbors of said planographic cylinder, a lever system actuating said eccentric bushings, a cam upon said main cylinder shaft actuating said lever system, damping and inking mechanisms for said planographic plate upon said main cylinder, and means whereby said last named damping and inking mechanisms are thrown out of the operative relation to said printing and impression surface upon said main cylinder.

24. A printing machine, embodying therein a main impression cylinder carrying a printing and impression surface thereon, and means whereby a planographic plate may be attached thereto, a planographic cylinder adapted to transfer an impression to the printing and impression surface of said main cylinder, eccentric bushings for the arbors of said planographic cylinder, a lever system actuating said eccentric bushings, embodying therein a crank shaft, one crank of which is adapted to impart movement to said lever system, and another crank of which is adapted to receive power for oscillating said shaft, a spring acting on said shaft to normally force said planographic cylinder into the operative relation to said impression and printing cylinder, a cam upon said main cylinder shaft actuating said lever system, damping and inking mechanisms for said planographic plate upon said main cylinder, and means whereby said last named damping and inking mechanisms are thrown out of the operative relation to said printing and impression surface upon said main cylinder.

25. A printing machine, embodying therein a main impression cylinder carrying a printing and impression surface thereon, and means whereby a planographic plate may be attached thereto, a planographic cylinder adapted to transfer an impression to the printing and impression surface of said main cylinder, eccentric bushings for the arbors of said planographic cylinder, a lever system actuating said eccentric bushings, embodying therein a crank shaft, one crank of which is adapted to impart movement to said lever system, and another crank of which is adapted to receive power for oscillating said shaft, a spring acting on said shaft to normally force said planographic cylinder into the operative relation to said impression and printing cylinder, a cam upon said main cylinder shaft actuating said lever system, damping and inking mechanisms for said planographic plate upon said main cylinder, and means whereby said last named damping and inking mechanisms are thrown out of the operative relation to said printing and impression surface upon said main cylinder.

said lever system, means whereby a movement of said shaft under said spring may be prevented, damping and inking mechanisms for said planographic plate upon said main cylinder, and means whereby said last 70 named damping and inking mechanisms are thrown out of the operative relation to said printing and impression surface upon said main cylinder.

26. A printing machine, embodying therein a main impression cylinder carrying a printing and impression surface thereon, and means whereby a planographic plate may be attached thereto, a planographic cylinder adapted to transfer an impression to the printing and impression surface of said main cylinder, eccentric bushings for the arbors of said planographic cylinder, a lever system actuating said eccentric bushings, embodying therein a crank shaft, one 85 crank of which is adapted to impart movement to said lever system, and another crank of which is adapted to receive power for oscillating said shaft, a spring acting on said shaft to normally force said planographic cylinder into the operative relation to said impression and printing cylinder, a cam upon said main cylinder shaft actuating said lever system, a ratchet tooth carried by and movable with said crank shaft, and a 90 pawl mounted upon a relatively fixed member and adapted to be thrown into engagement with said tooth, whereby a movement of said shaft under said spring may be prevented, damping and inking mechanisms for 95 said planographic plate upon said main cylinder, and means whereby said last named damping and inking mechanisms are thrown out of the operative rotation to said printing and impression surface upon said main 105 cylinder.

27. A printing machine, embodying therein a main impression cylinder carrying a printing and impression surface thereon, and means whereby a planographic plate 110 may be attached thereto, a plurality of planographic cylinders adapted to transfer an impression to the printing and impression surface of said main cylinder, eccentric bushings for the arbors of said planographic cylinders, independently operative means for moving said planographic cylinders away from said main impression and printing cylinder, comprising a lever system actuating said eccentric bushings, a cam upon 115 said main cylinder shaft actuating said lever system, damping and inking mechanisms for said planographic plate upon said main cylinder, and means whereby said last named damping and inking mechanisms are thrown 120 out of the operative relation to said printing and impression surface upon said main cylinder.

28. A printing machine, embodying therein a main impression cylinder carrying a 130

- printing and impression surface thereon, and means whereby a planographic plate may be attached thereto, a plurality of planographic cylinders adapted to transfer an impression to the printing and impression surface of said main cylinder, eccentric bushings for the arbors of said planographic cylinders, independently operative means for moving said planographic cylinders away from said main impression and printing cylinder, comprising a lever system actuating said eccentric bushings, a cam upon said main cylinder shaft actuating said lever system, movable frames, each carrying a damping mechanism acting upon said planographic cylinders respectively, means normally forcing said frames and said mechanisms into the operative relation to said planographic cylinders, said frames being held in engagement with the arbors of said planographic cylinders whereby said damping mechanisms will receive simultaneous and co-extensive movement with said planographic cylinders, damping and inking mechanisms for said planographic plate upon said main cylinder, and means whereby said last named damping and inking mechanisms are thrown out of the operative relation to said printing and impression surface upon said main cylinder.
29. A printing machine, embodying therein a main impression cylinder carrying a printing and impression surface thereon, and means whereby a planographic plate may be attached thereto, a plurality of planographic cylinders adapted to transfer an impression to the printing and impression surface of said main cylinder, eccentric bushings for the arbors of said planographic cylinders, independently operative means for moving said planographic cylinders away from said main impression and printing cylinder, comprising a lever system actuating said eccentric bushings, a cam upon said main cylinder shaft actuating said lever system, damping and inking mechanisms for said planographic plate upon said main cylinder, and means whereby said last named damping and inking mechanisms are thrown out of the operative relation to said printing and impression surface upon said main cylinder.
30. 29. A printing machine, embodying therein a main impression cylinder carrying a printing and impression surface thereon, and means whereby a planographic plate may be attached thereto, a plurality of planographic cylinders adapted to transfer an impression to the printing and impression surface of said main cylinder, eccentric bushings for the arbors of said planographic cylinders, independently operative means for moving said planographic cylinders away from said main impression and printing cylinder, comprising a lever system actuating said eccentric bushings, a cam upon said main cylinder shaft actuating said lever system, movable frames each carrying a damping mechanism acting upon said planographic cylinders respectively, a plurality of bell crank levers, one arm of each of which is pivotally connected to one of said frames, a spring acting upon the other arm of each said levers whereby said frames and said mechanisms are normally forced into the operative relation to said planographic cylinders, said frames being held in engagement with the arbors of said planographic cylinders whereby said damping mechanisms will receive simultaneous and co-extensive movement with said planographic cylinders, damping and inking mechanisms for said planographic plate upon said main cylinder, and means whereby said last named damping and inking mechanisms are thrown out of the operative relation to said printing and impression surface upon said main cylinder.
30. 30. A printing machine, embodying therein a main impression cylinder carrying a printing and impression surface thereon, and means whereby a planographic plate may be attached thereto, a plurality of planographic cylinders adapted to transfer an impression to the printing and impression surface of said main cylinder, each said cylinder being provided with a damping mechanism and an inking mechanism, means whereby either of said inking mechanisms may be thrown out of the operative relation to its cylinder, or both said cylinders may be simultaneously thrown out of such operative relation, eccentric bushings for the arbors of said planographic cylinders, independently operative means for moving said planographic cylinders away from said main impression and printing cylinder, comprising a lever system actuating said eccentric bushings, a cam upon said main cylinder shaft actuating said lever system, damping and inking mechanisms for said planographic plate upon said main cylinder, and means whereby said last named damping and inking mechanisms are thrown out of the operative relation to said printing and impression surface upon said main cylinder.
31. A printing machine, embodying therein a main impression cylinder having thereon an impression and printing surface and means whereby a planographic surface may be attached thereto, means adapted to transfer an impression to said impression surface, means for shifting said last named means to move them out of the point of engagement with said planographic surface upon said main cylinder, a damping mechanism carried by an oscillatory frame, means normally forcing said damping mechanism toward said main cylinder, a slide engaging said frame, a cam moving with said main cylinder and so set as to oscillate said frame and hold said damping mechanism out of engagement with said printing and impression surface upon said main cylinder, an inking mechanism arranged beyond said damping mechanism, means for shifting said inking mechanism away from said main cylinder during that period when said printing and impression surface is passing said inking mechanism, and a multi-revolution printing and impression cylinder.
32. A printing machine, embodying therein a main impression cylinder having thereon an impression and printing surface and means whereby a planographic surface may be attached thereto, means adapted to transfer an impression to said impression surface, means for shifting said last named means to move them out of the point of engagement with said planographic surface upon said main cylinder, a damping mechanism carried by an oscillatory frame, a spring normally forcing said damping mechanism toward said main impression cyl-

inder, means in conjunction therewith whereby the pressure can be regulated or eliminated, a slide engaging said frame, a cam moving with said main cylinder and so set 5 as to oscillate said frame and hold said damping mechanism out of engagement with said printing and impression surface upon said main cylinder, an inking mechanism arranged beyond said damping mechanism, 10 means for shifting said inking mechanism away from said main cylinder during that period when said printing and impression surface is passing said inking mechanism, and a multi-revolution printing and impression cylinder.

33. A printing machine, embodying there-in a main impression cylinder having there-on an impression and printing surface and means whereby a planographic surface may 20 be attached thereto, means adapted to transfer an impression to said impression surface, means for shifting said last named means to move them out of the point of engagement with said planographic surface upon said main cylinder, a damping mechanism adapted to coöperate with said planographic plate upon said main cylinder and to be moved out of the point of engagement while said printing and impression surface is passing same, a frame carrying inking rollers beyond said damping mechanism, means acting upon said frame to normally force said inking rollers into engagement with the planographic surface upon said main cylinder, a slide engaging said plate, a cam rotatable with said main cylinder and adapted to actuate said slide to force the inking rollers away from the printing and impression surface while it is passing said rollers, and 35 a multi-revolution printing and impression cylinder adapted to receive an impression from said planographic plate and to coöperate with the printing surface upon said main cylinder to simultaneously print upon both sides of a sheet of paper.

34. A printing machine, embodying there-in a main impression cylinder having there-on an impression and printing surface, and means whereby a planographic surface may 50 be attached thereto, means adapted to transfer an impression to said impression surface, means for shifting said last named means to move them out of the point of engagement with said planographic surface upon said main cylinder, a damping mechanism adapted to coöperate with said planographic plate upon said main cylinder and to be moved out of the point of engagement 55 while said printing and impression surface is passing same, a plurality of frames carrying inking rollers beyond said damping mechanism, means acting upon said frames to normally force said inking rollers into engagement with the planographic surface upon said main cylinder, a plurality of

slides engaging said plate, a cam rotatable with said main cylinder and adapted to actuate said slides to force the inking rollers away from the printing and impression surface while it is passing said rollers, and a multi-revolution printing and impression cylinder adapted to receive an impression from said planographic plate and to coöperate with the printing surface upon said main cylinder to simultaneously print upon both sides of a sheet of paper.

35. A printing machine, embodying there-in a main impression cylinder having there-on an impression and printing surface, and means whereby a planographic plate may be attached thereto, means adapted to transfer an impression to said impression surface, means for shifting said last named means to move them out of the point of engagement with said planographic surface upon said main cylinder, a damping mechanism adapted to coöperate with said planographic plate upon said main cylinder and to be moved out of the point of engagement while said printing and impression surface is passing same, a plurality of frames pivoted together to form lazy tongs levers, said frames carrying inking rollers, a spring connecting the free ends of said lazy tongs lever frames whereby said inking rollers are normally forced toward said main impression cylinder, a plurality of slides engaging said plate, a cam rotatable with said main cylinder and adapted to actuate said slides to force the inking rollers away from the printing and impression surface while it is passing said rollers, and a multi-revolution printing and impression cylinder adapted to receive an impression from said planographic plate and to coöperate with the printing surface upon said main cylinder to simultaneously print upon both sides of a sheet of paper.

36. A printing machine, embodying there-in a main impression cylinder having there-on an impression and printing surface and means whereby a planographic surface may be attached thereto, means adapted to transfer an impression to said impression surface, means for shifting said last named means to move them out of the point of engagement with said planographic surface upon said main cylinder, a damping mechanism adapted to coöperate with said planographic plate upon said main cylinder and to be moved out of the point of engagement while said printing and impression surface is passing same, a reciprocatory frame and means for moving same in its entirety toward and from said main cylinder, said frame supporting a frame, carrying inking rollers, beyond said damping mechanism, means acting upon said frame to normally force said inking rollers into engagement with the planographic surface upon said main cylinder, a slide engaging said plate,

mounted in bearings having a fixed relation to said main cylinder and adapted to bear against said inking roller carrying frame whereby with the movement of said reciprocatory frame, said slide and said ink roller frames will be automatically coupled and uncoupled, a cam rotatable with said main cylinder and adapted to actuate said slide to force the inking rollers away from the printing and impression surface while it is passing said rollers, and a multi-revolution printing and impression cylinder adapted to receive an impression from said plano-

graphic plate and to coöperate with the printing surface upon said main cylinder to simultaneously print upon both sides of a sheet of paper.

In witness whereof, I have hereunto affixed my signature, in the presence of two subscribing witnesses, this 6th day of November, 1911.

CHARLES A. STURTEVANT.
